C. W. Richter

UNITED STATES PATENT OFFICE.

CHARLES W. RICHTER, OF MADISON, GEORGIA.

LAMP.

Specification of Letters Patent No. 26,295, dated November 29, 1859.

To all whom it may concern:

Be it known that I, C. W. RICHTER, of Madison, in the county of Morgan and State of Georgia, have invented a new and Improved Lamp; and I do hereby declare that the following is a full, clear, and exact description of the same, reference being had to the annexed drawings, making a part of this specification, in which—

10 Figure 1, is a sectional elevation of my invention. Fig. 2, is a horizontal section of the same, taken in the line x, x , Fig. 1. Fig. 3, is a horizontal section of the same, taken in the line y, y , Fig. 1.

15 Similar letters of reference indicate corresponding parts in the several figures.

The object of this invention is to obtain a lamp for burning the heavier grades of coal oil with a good illuminating flame.

20 The invention consists in a novel means employed for adjusting or raising and lowering the wick within the wick tube, so that the wick is allowed to remain loose and free from pressure within the tube, thereby 25 favoring the capillary ascent of the viscous oil and insuring a proper supply of the same to the flame.

To enable those skilled in the art to fully understand and construct my invention I 30 will proceed to describe it.

A, represents the body and font of the lamp, which may be constructed in any of the known ways, and B, is the burner which is screwed into the top of the font as usual. 35 This burner B, is the one most generally used for burning coal oil and known as the "Vienna burner" it being supplied with three sets of perforations a, b, c , as shown clearly in Fig. 1, which supply the flame 40 with air both at the inner and outer side of the cap d.

The wick tube e, may be constructed and arranged as usual but the means employed for raising and lowering it is different. 45 This device is formed of a short bar f, which is slotted transversely as shown at f' , and has a fulcrum pin g, passing through the slot. At the inner end of the bar f, a toothed plate r, is attached the form of 50 which is shown clearly in Fig. 3. In the tube e, and opposite the toothed plate r, a slot s, is made, shown in Figs. 1, and 3. The bar f, projects through a slot t, in the side of the burner and when the wick a, in 55 the tube e, is properly adjusted the bar f, is drawn outward so that the toothed plate

r, will be free from the wick. This result is permitted on account of the slot f, through which the fulcrum pin g, passes. When the wick is to be adjusted the bar f, is shoved inward so that the plate r, will be in contact with the wick and the latter may consequently be raised and lowered by operating the bar f, on its fulcrum pin. By this device the wick n, is not compressed as is 65 the case where the usual toothed pressure wheels are employed and consequently the oil is allowed to ascend freely up the wick. This is an essential feature of the invention for the heavy oils are so viscous that a loose 70 wick is required, any obstruction produced by pressure retarding the ascent of the oil and preventing a proper supply of the same to the flame. Another difficulty attending the use of pressure rollers is, that even when 75 bearing slightly against the wick, they compress to a certain degree the parts against which they are in contact, the intervening parts being loose, and the flame is supplied 80 unequally with oil the loose portion supplying an excess over the compressed parts and an uneven flame and one liable to smoke is the result. By my invention this difficulty is avoided for the wick need not be at all 85 compressed but merely picked up, as with a pin, without in the least injuring its capillarity.

Another essential feature in burning coal oils,—those of the heavier grades,—is a sufficient draft in order to supply the flame with 90 oxygen. This I effect by placing a supplemental cap v, on the upper part of the burner and just above the uppermost set of perforators c, see Fig. 1. The cap v, is simply a short metal annular plate perforated as shown at u and provided with a rim a', within which the base of the chimney b', is fitted. This supplemental cap v, it will be seen, holds the chimney and at the same time supplies the flame with an extra draft 100 indicated by the red arrows. It also admits of an enlargement of the chimney immediately surrounding the flame rendering the same less liable to break than usual and also serving as a reservoir to keep the flame 105 encompassed with a supply of warm oxygen to favor proper combustion. This cap v, however has been previously used and does not form a part of this invention.

I do not claim as new any parts herein 110 described as forming the "Vienna burner", nor do I claim broadly a wick fitted loosely

within its tube, nor the supplemental cap *v*, but,

I do claim as new and desire to secure by Letters Patent—

5. The employment or use of the wick adjuster, formed of the bar *f*, provided with a toothed plate *r*, at its inner end and so

arranged as to have a certain degree of longitudinal adjustment in relation with the wick *n*, for the purpose set forth.

CHAS. W. RICHTER.
